UNITED STATES PATENT OFFICE.

JOHN P. TARBOX, OF GARDEN CITY, NEW YORK.

SOUND-PRINTING MACHINE.

Original application filed November 12, 1921, Serial No. 564,621. Divided and this application filed January 1, 1923. Serial No. 610,083.

My invention relates to what I term a sound printing machine, that is a system of printing through a control exercised by a device responsive to tone signals. These signals may be of any chosen character whatsoever, code or otherwise. In it the signals are sufficiently differentiated by characteristically different frequencies or otherwise to bring about each the response of the different portions of the control mechanism employed. By proper division of the chosen signals into groups and syllabic subgroups, the printing may take the form of code words, phrases and sentences, and may be divided into paragraphs and epistles. Suitably manually operable keys are provided for use when desired as an alternate or a conjunctive agency to the signals. Moreover, the arrangement of the control mechanisms is such that they may be grouped together for compound control by several signals of a single printed character, by means of which the printed code may be punctuated, and use may be made therein of numeral and figure characters. Still further mechanisms are combined with the foregoing for the dating and initialing, both for addressor and addressee, the number of pages, for record feeding, and the making of duplicate records.

My invention is shown diagrammatically in the accompanying drawings;

Fig. 1 shows diagrammatically the typewriting mechanism per se including the carriage, the type bars, actuating elements therefor, and auxiliary controlled and control devices;

Fig. 2 shows what I term the register mechanisms, and the page numbering device;

Fig. 3 shows additional register mechanisms and the normally operable control keys of the machine;

Fig. 4 shows one form of voice operated control device, or what I term a primary vibrational control element;

Fig. 5 shows another form of the same;

Fig. 6 shows the circuits of the dating and initialling devices;

Figs. 7 and 8 are side elevation and transverse section respectively of an element of the register mechanism.

Fig. 9 is a longitudinal vertical section of a primary vibrational control element.

Fig. 10 is a similar section of another form 55 of the same;

Fig. 11 is a front elevation of a diaphragm used in the form of Fig. 9.

Fig. 12 is a longitudinal vertical section of still a third form of the type of Figs. 9 60 and 10;

Fig. 13 is a diagram of an intermediate register system making use of successively acting relays;

Fig. 14 is a diagram of change spelling 65 connections which may be used if desired;

Fig. 15 is a front elevation of a proposed special form of typewriting machine for this work;

Fig. 16 is an end elevation of the same; 70

Fig. 17 is a schematic view of the details of the type bar mechanism;

Figs. 18 to 21 are respectively diagrams on a large scale of the primary contact banks in certain step by step switches used in 75 Figs. 2 and 6.

This application is a division of my application S. N. 564,621, filed Nov. 12, 1921, and is directed particularly to those forms of the tone operated control device shown 80 in Figs. 4 and 5 and some other features not covered in the patent application such as the change spelling connections of Fig. 14. These tones may be produced by the human voice, or by any other means, and wherever 85 in this specification the word "voice" is used, it is understood in this sense and understood that it is intended to produce tones. On the other hand, it is recognized that there are other characteristics of phonetics. 90

In Fig. 1 C designates the carriage and platen of any standard typewriter, and B—B are the horizontal type bar beams, shown in section. To these the type bars are connected as usual. The carriage and platen 95 C are shown as the traversing elements of the machine. If desired instead the "basket" of type bars may be made the traversing element. This has the advantage that the automatic feeding of paper to the platen 100 from rolls and duplicating by a continuous band of carbon, as shown in Fig. 16, is not interfered with.

The carriage is traversed to the left by

spacing device S_d , and to right by traversing motor T_m , the latter geared to the carriage or by any suitable means, a shaft and pinion being shown.

The paper feed from line to line is accomplished by an electromagnetically actuated line feed device L_f , the mechanical features of which may be of any of the well known forms. The paper feed of greater extent than the line feed is accomplished by a feed motor P_f geared to the axis of carriage C by means of the extended shafts and gears g , one of which is splined on shaft s . A conducting segment t on one end of the carriage, co-acting with brakes $b-b'$ which bear upon it thru perforations $p-p'$ in the paper, has to do with the control of the motor P_f of the paper feed device. The paper is fed from a roll as shown in Fig. 16.

The "Caps." shift device is shown at the right and designated C_s , while the "Figs." shift device is designated F_s .

Left and right marginal switches l_m and l_m' control the marginal operations of the various devices. The right hand marginal switch l_m' (which appears on the left of the figure) is cam operated by cam roller o , connected with the carriage C , while the left hand marginal switch l_m is operated by shaft s of the platen or other equivalent means.

The type beams $B-B$ are electromagnetically actuated by actuating magnets A_m , shown as of the solenoid type and having each two windings w' , w^2 , acting on a common core or armature c , adjustably connected with the type beams.

The register mechanisms of Fig. 2 are designated PH and SR respectively. PR is the primary register which receives the translated controlling energies of the voice, temporarily registers or stores them, and thereafter releases the same to operate the actuating magnet A_m connected with the type bars. It consists of a plurality of devices D , one for each character or less, and which are controlled in their operations by a distributing device DD (Fig. 2) and a releasing device RD (Figs. 1 and 2).

One construction of the registering devices D is shown in detail in Figs. 7 and 8, a bank of contacts comprising a plurality of tiers e (in this case four are shown) are jointly controlled by register magnet rm . There are five or more contacts to each tier (Fig. 7) and the lowermost is connected in each case to a vertically extending spring strip v , which are biased at their bottom ends toward the tier e by their own spring or a separately applied spring. The upper ends of strips v are provided with projections i adapted to be engaged commonly by armature u of magnet rm , whereby the strips v are raised and the contacts of any tier e are closed. The lower ends of strips v by

reason of their bias when they are raised to close the contacts e move laterally over and abut against the top of a common holding bar h . Parallel to the bar h are upper and lower cam shafts us and ls , carrying sets of cams c' , c^2 , one cam in each positioned to engage each vertical strip v . The cam shaft us is operated from the distributing device DD of the register mechanism PR (Fig. 2), while the cam shaft ls is operated by gearing connection gc with release device RD (Figs. 1 and 2). The sets of cams c' , c^2 associated with all of the devices D bear the same angular relation to each other, and the individual cams c' of each set successively engage in linear order vertical strips v of the tiers e with their projections i . By projection of the cams c' on shaft us , the strips v may one after another be moved forwardly to place projections i in position to be engaged by the outer end of armature u , the normal position of the strips v being with projections i clear of armatures u . By projections Z of cams c^2 of shaft ls , the lower ends f of strips v may be one by one pushed from holding bar h against which they come to rest when strips v are raised, as aforesaid, and the contacts thereby held closed or opened.

Referring again to Fig. 2, t' to t^4 are four battery trunk conductors, common to all the registering devices D and having respectively contacts $o'-o^4$ in the respective tiers e' to e^4 of devices D . Each winding w' of actuating magnet A_m , Fig. 1, has a contact ca in each tier $e'-e^4$ commonly connected therewith by multiple conductor 15.

These trunks t' to t^4 are successively connected to a battery by switching device ds . Device ds is a step by step device controlled by type bar link switches bs in multiple closing or stepping magnets sm of the device.

Device DD , driving shaft us , is on the other hand controlled by contacts cd in the tiers e' to e^4 of the devices D , closing the circuits of stepping magnets em' by way of conductors $20'$ to 20^4 , one for each tier e' to e^4 .

The portion of the primary register PR shown in Fig. 3 is associated with the controlling keys of the machine designated SYL (syllable), SUB (subscripture), PAR (paragraph), $TRAV$ (traverse), SPC (space), $CAPS$ and $FIGS$ (capitals and figures), $LINE$ and $FEED$. Substantially the entire manual control of the machine is had thru these nine keys, and normally only one of them, the "CAPS" key is in use. A group of relays R has to do with the connection between the controlling keys and the devices D of the register and other elements of the machine.

The secondary register SR of Fig. 2 is structurally in most respects similar to the

primary register PR. Four trunks t^5 to t^8 have contacts o^5 to o^8 in devices D, and are controlled by a contributing switch DS². Cam shafts us is stepped by device DD² governed as before by contacts cd in devices d. Shaft ls however is not driven from distributing devices DS², but is oscillated by magnet om . The function of this portion of the secondary register SR is to register 10 the initials of the addressee and thereafter effect the impression thereof on each page written. A device D is provided for each letter of the alphabet as in the case of mechanism PR.

15 Two or more devices DD shown on the right hand are permanently associated with the special trunk St of the group t^5 to t^8 , and the connection is made by these devices D in accordance with the control of page 20 numbering switch PS. A special oscillable release shaft sl is operated by magnet mo . The function of this portion of the device is to successively number the pages written.

Fig. 4 shows one form of primary vibrational control element. It comprises a special transformer F, and associated primary transmitter T controlled by relay transmitter T', circuit PC and resonant secondary circuits sc . The secondary sc govern relays 25 Re, which in turn control the magnets Rm of register devices D (Fig. 3). Circuits sc are each tuned to respond to a characteristic sound signal, differentiated by frequency, or otherwise, various combinations of resistances, inductances and capacities being used for that purpose as shown. Any combination found suitable may be used in any circuit. The coherers co associated with these 30 circuits may be of any known type, and decohering (if necessary with the type) 40 accomplished in any known way.

Keys A', B', C', etc. are provided on the register side of relays Re for the manual operation of the machine, and keys h on the transmitter side for manual operation thru relays Re.

45 The mechanism SM at the lower right is the spacing and syllabizing mechanism which is operated altogether automatically. MG is a motor generator set of small size furnishing current for the operation of the various devices of the machine by positive and negative bus wires PB and NB.

50 The mechanism DA of Fig. 6 is the dating mechanism. It comprises six manually set number switches Ns having contacts connected in multiple to the magnets Am of the numeral characters, trunks ns leading therefrom, and a switch ES controlling the energization of the trunks.

55 The mechanism Im is the initialling mechanism. It comprises three or more manually set initial switches Is having contacts multiply connected to the actuating magnets Am of the letter characters, and like the

mechanism DA, trunks us leading to and energized by an energizing switch ES'.

The various details of the machine and its circuits will be described in connection with the operation.

Sound signals are projected into the transmitter T. Thru the action of transmitter circuit 11 on repeater transmitter T (or upon any known form of repeater device) the amplitude, intensity and volume of the waves is increased. Acting on transformer F thru primary winding pc, the waves may be still further increased in size. The waves of each letter energizes one or more predetermined tuned circuits sc , and thru associated coherers or detectors co close the circuits of associated direct current relays RE. Each relay (or combination of relays as will appear hereinafter) controls by its contacts a circuit as follows, including a magnet rm of register devices D. Bus NB at the relays, conductors 12, contacts 13 (or 13 and 13'), according to the combination of relays Re), conductor 14, magnet rm and bus PB at devices D. Magnet rm being energized 80 pulls up that tier of contacts e' to e^4 whose vertical bar v is at that time pushed forward by cams c' on shaft us. We will assume this tier is tier e' connecting with trunk t' (see Figs. 7 and 8). The circuit 85 of the associated actuating magnet Am is therefore closed from trunk t' , thru contacts ca of tier e' , (which may be identified in Fig. 2) conductor 15, winding w' of magnet Am, and to the bus PB, then to bus NB 90 at switch ds , arm 16^a, contact 16 of contacts 16, 17, 18, 19 and 16', 17', 18', 19' (connected respectively in diametrically opposite pairs with trunks t' to t^4) to trunk t' . Winding w' of magnet Am becoming energized 95 draws its core or armature down and operates the type beam B to print the letter character dictated.

When tier e' of device D was pulled up it closed by contacts cd one of the four loops 100 20' to 20¹ which loops are multiplied respectively to the contacts cd of the various devices D. This energizes one of the four (only one is shown) actuating magnets sm' 105 associated with device DD, and steps the upper cam shaft us, thus rotating the shaft us one step (shown as one-quarter revolution, but it may well be less) and pushing forward the actuating bars v^2 (Figs. 6 and 7) of the second tier e^2 of each device D, 110 into position to be engaged by the armatures of magnets rm. In the meantime the bar v' previously actuated is held in actuated position by the engagement of its foot f , 115 with the common holding bar h (see Figs. 7 and 8). Therefore when the armature of magnet rm drops back upon degenerization the previously actuated contacts of tier e' remain in actuated position. This is true 120 of each tier of contacts, and moreover each 125

105

115

120

125

130

tier closes its associated loop of the group 20' to 20⁴, each thus stepping the device DD and shaft *us* one step. Thus is secured a very important result. Characters successively registered on primary register PR are identified each with a different trunk of the group *t'* to *t⁴*, since each tier of each group *e'* to *e⁴* makes connection with a different one of the trunks. This admits of sound signaling at any and all rates within wide variations, and in case a group is rapidly made, several code characters may be registered on register PR during the printing of one. By increasing the number of tiers of contacts *e'* to *e⁴* per device D and the number of trunks *t'* to *t⁴* the permissible number of advance registrations may be increased.

Each time an actuating magnet Am pulls up over a circuit closed from a device D of the register mechanism, at or near the limit of movement of the type beam B, a limit switch *bs* is actuated to close the loop 21 which closes the circuit of an actuating magnet *sm* of stepping device RD, thus stepping switch *Ds* one point. Thus the wiper 16^a energizes trunks *t'* to *t⁴* successively from bus NB, and in the same order as the trunks are associated by cams *c'* with tiers *e'* to *e⁴* in the stepping of device DD. By this means the plurality of registered characters are successively printed, not in the time succession in which they are signaled and registered, but in accordance with the natural operating speed of the typewriting machine itself. This is the ideal method, for irrespective of variations in rapidity of signaling, between one syllable and another, one word and another, and of different operators, the printing speed is independent, and determined at all times by the natural (which is by far the most rapid and smooth) speed of the machine. Nor do variations in the rate of action of any type bar cause any disturbance in the regular operation, each successively operated bar being dependent upon the rate of operation of the precedingly operated bar for the initiation of its operation.

Obviously this method of operation is of value in manually operated typewriters as well as typewriters of this type, for the rates of operation on the individual type bars are independent of the rate and the time order of succession of operation of the various keys. Thus crossing or sticking of type bars, and disorderly operation of any sort is positively prevented. Controlling keys A', B', C', etc., Fig. 4, are provided in shunt to the relays *Re* (Figs. 4 and 5) for manual operation and control of the circuits of the register magnets *rm*.

The number of trunks *t'* to *t⁴* may be increased or decreased at will to suit any existing conditions, the associated apparatus

being readily allowed by the skilled operator to suit in point of number of steps, cams, contacts, etc.

The trunks *t'* to *t⁴* are successively released from devices D by the stepping of lower cam shaft *ls* which pushes the feet *f* from bar *h*. This stepping takes place from and in synchronism with the stepping of switch *ds*, being connected therewith by chain or other gearing connection *gc*. The cams *c²* of shaft *ls* are arranged in the same order, but one step behind as respects contacts 16 to 20, etc. of switch *ds*, so that upon the energization of each trunk by switch *ds*, the preceding one is released by cams *c²* from the then associated device D. In other words the release of any trunk takes place as the next succeeding trunk is energized. Therefore there is always available one or more free trunks. As many as three of the four (or four of five, etc.) may be tied up to devices D at one time but upon momentary slowing up or cessation of dictation the printing catches up and they are successively freed, whereupon they are all available. The adaptability of this method as between operator and machine is full and complete. The personal equation of the dictator alters in no way the orderly operation of the machine.

The operation of all other elemental letter controlling and actuating circuits from the vocal analyzer of Fig. 4 is substantially the same for each letter of the alphabet and hence need not be individually traced herein. There is one exception to be found in the circuits of those characters identified by the energization of a plural number of resonant circuits *sc*. Suppose one signal sound characterized by frequency or wave form *a*, another by *d*, and a third by both *a* and *d*. If simple circuits as that just traced from relays *Re* be used then the signaling of the third signal will pull up register devices D of both the first two. But combination circuits are used as shown for the sake of illustrating in connection with the circuits controlled by the A' and D' keys (Fig. 4.). The A' circuit 14 governed by normally opened contacts 13 of the A' relay *Re* extends thru normally closed contacts 13', and vice versa, whereby if either the A' relay or the D' relay *Re* pulls up singly, the particular individual circuit A' or D' is closed to conductor 14, but if both the A' and D' relays *Re* pull up in response to making of a third signal, both the A' and D' circuits are opened at contacts 13'; and instead a third circuit 14 of the C' key is closed thru normally open contacts 13² on relays of the A' and D' circuits in series. Thus are combinations and interlocks made to effect registration or differentiation of the complex sounds from each other. The skilled engineer may work out

as many of these combination and interlocks as desirable, using any of the combinational and interlocking circuit arrangements known to the art, whereby each signal sound is positively identified with the circuit 14 of a single code character A', B', C', etc. including a single register magnet *rm*.

Capital letters.

- 10 Any signal or group of signals may be code printed in capital letters by simply pressing the CAPS control key of Fig. 3. The pressure of this key closes the circuit of caps magnet *Cs*, Fig. 1, as follows; Bus 15 NB, caps key, conductor 22' device D, 22 (Fig. 6, Fig. 1) magnet *Cs* and to bus PB. This shifts carriage C, and as long as the CAPS key is held depressed, all sound signals made are coded in capital letters. If, 20 however, the CAPS key is only momentarily pressed the CAPS magnet *Cs* locks itself up thru normally closed contacts 23 and 24 of relay 25 by conductors 26 and 27, from bus NB. Relay 25 is in one arm of loop 25 21 which is closed each time a type bar B is actuated. Hence upon printing of the first letter after the caps key is released, the locking circuit of *Cs* is broken at 23, 24, and the carriage C returns to normal position. Thus the first letter only of each code sentence is capitalized. It is necessary only to use this key at the beginning of signaling, as a rule, as will be seen hereafter.
- 30 The time of closure of the loop 21 and consequent energization of relay 25 may be varied at will through adjustment of cores C or their connected parts, which strike contacts *bs*, so as to bear any desired relation to the stroke of the type bars. The magnet *Cs* is shown as operating thru lever 132 and abutment 133 directly upon one end of the carriage C, but it will be understood that this showing is diagrammatic, and that the magnet *Cs* (and the magnet *Fs*) operate upon any of the standard carriage shifting levers or other parts now used for that purpose.

Spacing.

- 50 Spacing, as aforesaid, is, or may be entirely automatic. The method made use of is one of differentiation between the time intervals between the making of successive signals and the making of successive group signals, or the differentiation of time intervals between syllables or subgroups of the same group from the time intervals between successive groups. There are two ways disclosed of accomplishing this differentiation. The first, embodied in Fig. 4, depends upon the presence or absence of the fundamental note in any signal. A special winding 28 is placed on transformer F, and operatively connected by special

timed circuit 29 and coherer *co*, with the special relay 30 of the group Re. The circuit 29 is tuned to respond to the fundamental only. Consequently relay 30 is energized only when the fundamental tone is being sounded. Now by making sound signals carefully in syllables, it will be observed that the cessation of fundamental tone in each case marks the division of the group signal into syllables, and furthermore marks the distinction between group signals. The fundamental ceases for a longer period between group signals than between syllables thereof, and we can and do at will vary the difference in length between these periods, generally to increase the length of the period between groups. This latter results in succinctness.

Now the time of degenerization of the relay 30 measures the length of these periods. Relay 30 controls a relay 31 of the spacing mechanism *sm* by a circuit from PB, conductor 32, relay 31, and to bus NB. Relay 31 in turn controls by circuit NB, armature 34', front contact 35, conductor 36, a relay 37, of what is commonly known to the art as the "slow relay type". This relay is provided usually with a copper sheath for its case, whereby the time of its release or falling back is increased. As is well known in the art this type of relay may be constructed and adjusted to fall back more or less rapidly. With respect to the time of falling back of this relay the time of cessation of the fundamental as measured by relay 30 is compared. Relay 31 also when it pulls up energizes locking relay 40 over circuit NB, armature 41, front contact 42, conductor 43, relay 40 and to bus PB. Relay 40 locks up thru conductor 44, front contact 45, conductor 46, (Fig. 2) normally closed contacts 47, on dash register device D of register PR conductor 48 (Fig. 3), normally closed contacts 49 on space register device D, conductor 52 to negative bus NB. Contacts 47, 49 and 51 are opened whenever devices D are energized, being of the character of contacts 47 shown in Figs. 6 and 7. Thus relay 40 (Fig. 4) when locked up is unlocked upon the registration of any one of dash, traverse or space movements.

When relay 40 is locked up and relay 31 falls back a second locking relay 53 is pulled up from NB, armature 41, back contact 54, conductor 55, front contact 56 of relay 40, conductor 57, relay 53, conductor 58 (Fig. 2) (Fig. 1), left limit switch *lm'* when the same is closed and to battery PB. This relay 53, therefore, is pulled up when relay 31 falls back when the left limit switch *lm'* of the carriage C is closed, and this switch is arranged to be closed whenever the writing reaches the marginal limit at the end of each line and thru-out the right marginal space usually guarded by a bell for syllabizing.

Relay 53 locks up by conductor 59 to conductor 46 and over the same locking circuit as traced for relay 40.

Now relay 30 and hence relay 31, falls back each time the fundamental ceases, both between group signals and between syllables thereof. If between syllables the interval of deenergization is too short to permit the slow acting relay 37 to release, but each time 10 relay 31 falls back it partially closes the circuit of relay 53 at its back contact 54, thus continually testing for the marginal condition of closure for relay 53 brought about by the closure of limit switch lm' . Upon 15 finding such condition, whether between signal groups or between syllables thereof, relay 53 is energized. Pulling up and locking itself it closes one circuit and partially closes another, the first from bus NB by front contact 60, conductor 61 (Fig. 2), bell relay 62, and bus PB, and the second from bus NB, thru front contact 34' of relay 31, conductor 36, front contact 64 of relay 53, conductor 65 (Fig. 2), magnet rm of dash register D, to 20 PB, thus registering a dash for printing after the latest syllable signaled. Note that this registration takes place only when relay 31 pulls up when relay 53 has locked up on the marginal limit switch lm' , but it does 25 not always take place when these conditions are present.

If before relay 31 has pulled up, there has been time interval (during the absence of the fundamental tone) sufficient for slow relay 35 37 to drop back, this relay closes a circuit by its back contact 66, conductor 67, front contact 68 of the first locking relay 40, conductor 69 (Fig. 2) (Fig. 3) back contact 70 of relay 69^a, conductor 71, conductor 72 40 and magnet rm of the space register device spc , and to bus PB. Thus if there has been time for slow relay 37 to fall back a space is registered. The energization of the magnet rm of the space register opens contacts 45 49 in the locking circuit of relays 40 and 53, and they fall back, whereby when relay 31 again pulls up, the syllable register circuit previously traced is open at contact 64 of relay 53 and the dash register is not 50 energized.

Relay 37, as aforesaid, is a means of measuring the time interval of cessation of sound signaling or of the fundamental pitch of the sound as indicated by the time of deenergization of relay 31. Locking relay 40 functions principally as a means to enable the relay 31 to test for the marginal condition established by switch lm' on its back stroke only. In other words it 55 functions as would switching contact made by relay 31 in one direction only. Many forms of this are known and may be used. Relay 53 energized on the back stroke of relay 31 is an indicator of the existence of 60 the test condition sought by relay 31. -

To recapitulate, if when the test condition is indicated by relay 53, the interval of time permits relay 37 to fall back, the circuit 69 of the space register is closed and relay 53 deenergized, but if before this, the relay 31 70 again pulls up, the circuit 65 of the dash register is closed thru contacts of relay 53 and the relay 53 thereafter deenergized by the opening of contacts 47 in the locking circuit. In sound signals one has only to 75 make the time intervals between signal syllables less than that taken by slow relay 37 to fall back, and that between signal groups slightly greater, and spacing and syllabizing will take place automatically. 80

Now resuming at the point where the space register becomes energized, (Fig. 3) it will be noted that relay 69^a is deenergized only when the marginal test condition of switch lm' is absent. Thus the space register is 85 actuated only in the absence of the marginal test condition. When switch lm' is closed 69^a is energized over conductor 58 and by conductors 73 (Figs. 2 and 3) to NB. This shifts armature 74 from back contact 70 to 90 front contact 75 from which extends conductor 76 to the traverse register device D. Hence when relay 37 falls back with the printing on the margin, traverse is immediately registered instead of a space. This 95 causes operation of the traverse motor TM without delay as will be later described to shift the carriage C to the beginning of the next line.

When relay 37 does not fall back, relay 100 31 on pulling up on the marginal condition as aforesaid registers a dash. As in the case of traverse this registration is printed in order immediately following the last letter of the preceding syllable. In registration 105 when the marginal condition is present (not at other times) the dash register closes by front contacts 77 circuit from PB thru switch lm' , conductor 58, conductors 78 and 79 (Fig. 3) relay 80 and conductor 81 to NB. 110 Relay 80 locks itself to battery PB by conductor 82 thru contacts 83 on traverse register device D, and partially closes by contacts 84 the circuit of the traverse register D thru conductor 85 from conductor 76, 115 conductor 86 (Fig. 2), and back contact of dash register D to battery NB by conductor 87. Thus when a dash marks a syllable on the margin, traverse is registered upon the falling back of the dash register, 120 and the carriage C is traversed immediately upon the printing of the dash, as it should be, to the beginning of the next line.

Now the dash is a mark of punctuation, and as such is representative of its class. 125 Although limited space prohibits the showing, it is intended that the registry of any mark of punctuation marking the termination of a syllable, word, or numeral, and the like, shall cause the succeeding registry of 130

the transverse of the carriage C to the beginning of a new line. To this end the register circuits and devices of the said other punctuation marks will be associated whenever found desirable, with the circuits of the traverse register in the manner described in connection with the dash register.

There are some cases in which this association will be unnecessary on account of the occurrence of a space interval immediately following the sound signaling of the mark (for they are signaled as well as code letter characters), the timing relay 37 then registering traverse instead of space as previously set forth.

Obviously in the absence of the marginal test condition and the printing in the body of the lines, while the relay 31 continuously tests for the marginal condition, no syllables are marked as a result of such test, for relay 53 is deenergized until the marginal condition is found. On the other hand whenever timing relay 37 measures a space interval it closes by conductor 69 independently of relay 63, the circuit of the space register D thru the back contact of the now deenergized relay 69^a as traced above.

It has been said the bell relay 62 (Fig. 2) furnishes a guide to the dictator as to marginal shifting. This relay upon being energized by relay 53, closes one circuit, opens another, and locks itself up. The first circuit is that of the bell magnet 88 extending from PB thru front contact 89 by conductor 90 to the magnet and thence by conductor 91 to NB. The circuit opened is the bus PB of the code letter registers D, and the opening is at back contact 92. The locking circuit is by front contact 93 to conductor 94 (Fig. 1) to normally closed contacts 95 on the right hand limit switch lm, and to NB (disregard for the moment loop 168). Thus relay 62 remains locked up until the carriage C is shifted to the beginning of the new line whereupon it is unlocked. It should be mentioned by the way that the line feed is accomplished by the traverse action as in the standard Oliver machine, or else may be accomplished thru the actuation of the line feed mechanism Lf shown by closing its circuit by special contacts controlled from the traverse register, the circuit 144 of the traverse motor or switch lm. It may also be mentioned that the points of operation of the switches lm and lm' may be adjusted at will thru adjustment suitably provided for any of the associated parts as may readily be done by the skilled engineer in accordance with the already known marginal adjustments of standard typewriting machines.

Hearing the bell 96 rung by magnet 88 (Fig. 2), the operator signals the next syllable of the signal group as if nothing had happened and then stops. The code let-

ters of this next syllable or signal group are not registered, because bus PB is open at contact 92. Their making however enables relay 37 (Fig. 4) to measure the time interval and determine the syllabizing and spacing. This latter being accomplished, when relay 62 falls back it closes by contact 97, and conductor 98 (Figs. 3 and 4) the circuit of another bell 99 of the same or different tone from the bell 96, whereby the operator is advised to proceed signaling, which he does by beginning at the point where the first bell 96 sounded. The bells follow each other of course in quick succession.

Punctuation.

Punctuation marks are signaled and registered and printed, as are the code letters. This is accomplished by series circuits thru contacts of a plurality of devices D, those entering into the combination in any case being a portion or all of those code letter registers spelling the name of the punctuation mark. Thus for a semi-colon, the registers of letters SEM, etc. would figure in total or in part.

Referring to Figs. 2, 7 and 8, it will be seen that a number of registers D of the primary mechanism PR contain normally open sets of contacts 100 electrically insulated from each other. These may be mounted like contacts 47. Series conductors 101 are each completed by the closure of a plurality of sets of contacts 100. Conductors 101 extend from devices D not to windings w', but to windings w² of actuating magnets Am (Fig. 1), windings w² being connected with a special bus PB' separate from that PB associated with windings x' w'. The bus PB' is normally open at contacts 102 controlled by figures magnet Fs while the bus PB is normally closed at contacts 103 controlled by the same magnet. Thus normally when registers D are actuated by code letter group signaling windings w' are energized one from each individual register as aforesaid, over circuits 15, the closure of any one of the series circuits 101, being without effect owing to the break in bus PB' at 102. When numerals or punctuation marks are to be printed, however, the FIGS. Key (Fig. 3) is pressed down, whereupon Figs. magnet Fs becomes energized over circuit presently to be traced, closing 102 and simultaneously opening 103. Windings w' and circuits 15 are now disabled and windings w² and circuits 101 enabled.

Now the magnets sm of the trunk distributor DD are energized normally over circuits 20', to 20⁴ under control of the individual registers D, are shifted by magnets Fs from circuits 20' to 20⁴ to circuit 104, under control by switch 105 of the control switch RD (Fig. 1). Switch 105 comprises

a wiper 106 stepped over contacts 107 connected commonly with circuit 104 which circuit puts battery PB on magnets sm' of distributing device DD (Fig. 2). The magnets sm' are thus energized singly as the device RD is stepped by closure of circuit 21 (Fig. 1). The devices D are thus shifted from one trunk to another only upon the energization of the printing magnets w^2 .
 10 Thus the several letter registers D (as for instance SEM and I governing the circuit of semicolon printing magnet w^2) all pull up on the same one of the trunks t' to t^4 , which is as it should be for proper control thru master switch RD.

15 It is particularly to be noted that figure characters and not capital letters are code printed in this manner and further that any desired figure character whatsoever may be code signaled to the machine and will be code printed properly by it, the essential requisite being that each register combination shall be different from each other, and that each of the series circuits 101 shall be maintained electrically separated from each other.

20 To this end it is best that no single pair of contacts 100 be used in more than one circuit 101, duplicate pairs 100 being provided on each device D (see Fig. 7) when needed and all actuated simultaneously in the same manner.

25 When the FIGS. key (Fig. 3) is pressed to print the dictated figures, the circuit of the FIGS. shift magnet F_s is closed as follows; FIGS key (Fig. 3 from bus NB of the keys, conductor 129, Fig. register device and battery PB. The FIGS. register pulling up closes directly the circuit of figures shift magnet F_s from trunk t' (or t^2 to t^4) corresponding contact ca of tier e (see also Figs. 6 and 7), conductor 130 (all second contacts ca of tiers e are connected in multiple to conductor 130), as to conductors 40 15 of the character actuating magnets), conductor 130, Figs. 6 and 1, magnet F_s and battery bus PB, thence to bus NB at distributing switch ds , Fig. 1 wiper 16^a, contact 16 and trunk t' (or t^2 to t^4) back to contact ca of the FIGS. register of Fig. 3. When the FIGS. key is released the platen is at once returned to normal position, and the restoration of all circuits to normal effected.

55 *Automatic caps, shift from period.*

60 Whenever a period is printed the registration of a space and then of a capital for the beginning of the next sentence automatically follows. Upon the energization of circuit 101 of the period printing magnet 108 (Fig. 1), a relay 109 in series with printing magnet 108 is pulled up. This relay closes two circuits from bus NB, the one 110 from contact 111 and the other 112 from

contact 113. The first 110, extends thru Fig. 6 into Fig. 3, and thence thru normally closed contacts 114 on a relay 170 (presently to be described) to relay 116, and to PB. The second circuit 112 from relay 109 extends likewise thru Figs. 6 to Fig. 3, and thence thru a relay 117 to PB. Relay 116 of the pair 116, 117, being energized, closes a locking circuit 118 for itself thru front contact 119 and back contacts 120 on the space register SPC. Relay 116 also closes the energizing circuit of the space register by its front contact 121 and conductor 122 connecting with conductor 172 previously described. Thus a space is automatically registered and properly printed after each period. Promptly upon registration of the space the locking circuit 118 is broken and relay 116 returns to normal.

20 But relay 117 having become energized over circuit 112, closes by one of its front contacts 123 a locking circuit 124 for itself extending thru normally closed contacts on the CAPS register, and thereby not opened until the caps register pulls up. By its other front contact it partially closes circuit 126 of CAPS relay 125.

25 The operation of the space register SPC after a period, completes circuit 126 at contacts 127. Thereupon relay 125 pulls up, locks itself by 128 over circuit 124 previously traced, and closes circuit 22' of the register upon the energization of which both relays 117 and 125 are unlocked and fall back. All this takes place in a moment of time, but nevertheless in the orderly sequence set forth. Thus space following a period is registered on one trunk t' to t^4 and capitals on the next succeeding, just as in the case of letters and figures.

30 It is to be understood that although not shown in every case for the sake of clearness, every actuating magnet energized from the primary register PR contains a pair of contacts in multiple with those bs on loop 21 (Fig. 1), whereby the distributor switch RD is actuated one step for each energization of any such magnet.

35 The Caps, register CAPS closes upon the then waiting trunk t' to t^4 a circuit thru conductor 22 (Figs. 3 and 6 then Fig. 1) to caps shift magnets C_s . Upon the actuation of the spacing magnet S_d (Fig. 1) and which by the way is energized over a circuit 131 from the space register SPC, Fig. 3, Fig. 6 and Fig. 1, following the printing of the period, the ensuing step of the device RD energizes caps magnet C_s over the associated trunk t' to t^4 . C_s shifts the carriage C (the basket of type bars, or the equivalent) thru connection 132 with abutment 133, preferably separate from connection 134, and abutment 135 actuated by F_s . Unlike F_s however C_s does not break the normal connections of PB, for circuits 101 are not to

be used at this time, simple capitals and not figures being desired. Magnet Cs does however close a locking circuit 26, 27 for itself thru back contact 23 of the relay 25 in the 5 battery lead of loop 21. Thus magnet Cs is therefore locked up only until the first letter is printed, whereupon relay 25 unlocks its circuit at 23, 24, and the carriage C drops back to normal position for small letters and 10 the next letter printed will be a small letter. Relay 25 should be a fast relay as compared with actuating magnets w' and w^2 .

When all caps are desired it is only necessary to press and hold down key AC 15 which key breaks the locking circuit 26, 27 and independently closes the circuit of Cs by a path including conductor 139.

Space from comma.

20 Having traced the circuit entering into the automatic spacing and capitalizing following a period, (and for any other sentence terminal mark, as for instance question mark and exclamation mark), the circuits whereby spacing automatically follows a comma (or other similar subordinate marks, as for instance semi-colons, colons, dash, apostrophe, quotations, parenthesis, etc.) may be readily traced. Referring again to Fig. 1, the relay 25 140 by the side of relay 109 is in the circuit 101 of the actuating winding w^2 of the comma type bar COM. When this circuit is energized to print a comma, relay 140 closes by its own contact 141 circuit 110 (previously traced to relay 116) in the same manner as does relay 108. Thus a space is registered and the machine operated one space immediately following the comma (or other subordinate mark), the circuit connections being the same as in case of space following the sentence terminal marks. There is provided one relay 140 for each circuit 101 of a subordinate mark, but no additional relays 116 need be provided, the relays 140 commonly controlling relay 116 by contacts 141 wired thereto in multiple. The same is true of relays of the type of 109 as respects relays 116 and 117.

Line feeding.

50 Line feeding is accomplished automatically at the end of each line wherever that line terminates at the right margin of the page or not too close to the left margin. When it terminates at other points it may be manually brought about (or automatically, as mentioned before). In the first instance it results directly from the traverse of the carriage, as in the Oliver machine, but this instance will be described in connection with the automatic traverse of the carriage. In the second instance it is brought about by the pressure of the line feed key (LINE) (Fig. 3). This closes circuit 142 to the line register. In a manner entirely similar to that of the other registers the line register closes a circuit from one of trunks t' , t^4 to conductor 143 (Figs. 3, 6 and 1), and to the line feed magnet L_f (Fig. 1), which magnet is energized in turn and steps the platen the 70 proper distance. Magnet L_f has contacts (not shown) similar to contacts b_8 , closing loop 21, as indeed do all devices actuated thru register PR, the actuating magnets A_m being an example. Operation of the magnet L_f may be made direct from the line key as in the case of the Figs., magnet F_8 if desired. Operation thru register PR simply prevents possible untimely operation by the operator, since when operated thru the register, the printing of already registered dictation necessarily precedes any line movement of the carriage. In case of any control where it is desired to prevent untimely operation, the control may be carried thru a device D of register PR instead of being exercised direct from the control key.

Traversing.

Traversing is automatic from all points 90 lying on the right hand margin of the sheet. In connection with the automatic spacing described on page 16, the manner of closing of the circuit of the traverse register when relay 37 (Figs. 4 and 5) falls back with the 95 printing on the margin was disclosed. The traverse register is automatically substituted for the space, thru the energization of relay 69^a (Fig. 3) from the marginal switch l_m' (Fig. 1). The traverse register 100 closes the circuit of conductor 144 to one of the trunks t' to t^4 . Conductor 144 leads thru Figs. 3, 6 and 1 to traverse motor T_m , and T_m becomes energized immediately 105 after printing of the last letter of the syllable or word, or of the punctuation mark, to traverse the carriage. The traverse continues to the extreme left margin whereupon the limit switch l_m (Fig. 1) is operated by 110 the end of the shafts s or any other projection from the carriage, and conductor 144 is opened at contacts 145 (or thru any suitable relay) and motor T_m stops. This opening of the motor circuit should take place just 115 preceding the bringing up of the carriage against the usual marginal stops so that the inertia of the moving carriage may be in part spent before striking the stops. Additional breaking means may be used if desired.

While traversing at the margin is automatic, traversing to a new line from any point of a given line, as for instance when a sentence ends intermediate the ends of the line, may be manually brought about by simply pressing the traverse key TRAV of 125 Fig. 3. The pressure of this key closes the circuit of the traverse register, with identically the same result as previously de-

scribed, the traverse of the carriage (or basket of type bars) to the beginning of a new line.

Paragraphing.

The paragraphing key PAR of Fig. 3 also has to do with the traversing of the carriage, but instead of stopping at the beginning of a new line, the carriage is stopped finally short of the beginning of the new line in order to define the paragraph as usual. Referring to Fig. 3 it will be seen that pressure of the PAR key closes two circuits to battery PB, the one 146 and 76, to the traverse register, which produces traverse of the carriage, and the other, 147, to relay 148. Relay 148 pulling up locks itself thru contact 149 from battery NB, by conductor 150 (Fig. 6), normally closed pair of contacts 151 carried on oscillable shaft 152, conductor 153, and back to relay 148. By its contact 154, relay 148 closes circuit 155 (Figs. 3, 6 and 1) to normally open contacts 156 on right limit switch *lm*, thence by conductor 157 (Figs. 1 and 3) to magnet 158, the armature of which, 159, is connected to oscillable shaft 152. As soon therefore as the traverse has been completed magnet 158 is energized and rocks shaft 152 to bring abutment 160 and the contact 151 into the path of the end of shaft *s*, (same as shaft *s* in Fig. 1) or any other projection from the carriage C. Magnet 158 at the same time releases carriage C for movement to the left until shaft *s* engages stop 160. The said releasing mechanism is not shown, but is intended to be the same as or the equivalent of the well known release of the tabulating mechanism used in all machines today, and stop 160 and its companion stop 161 correspond in function to the tabulating stops. Any of the well known tabulating mechanisms may be used, magnet 158 simply constituting its actuating element. Stop 160 defines the paragraph position of carriage C, and when that stop is engaged by shaft *s*, normally closed contacts 151 in locking circuits 150, 153 are opened, and paragraph relay 148 (Fig. 3) is deenergized, thus opening the circuit of paragraph magnet 158. It will be noted that magnet 158 closes a locking circuit 162 for itself in shunt to contacts 156 of switch *lm*, thereby remaining energized until stop 160 is engaged by shaft *s*. In some tabulating release mechanisms this will not be necessary.

Relay 148, Fig. 3, during the time of its energization, also maintains closed contacts 163 which put battery FB upon conductor 177, contact 176 of relay 170, and one side of loop 168 extending (Figs. 3, 6 and 1) to conductor 94. Conductor 94 is that conductor over which the locking circuit of register disabling relay 62, Fig. 2 is closed. Loop 168 including in series contacts 163^a

of 148 and 176 of relay 170 is normally in series with contacts 95 on switch *lm*, and thus the relay 62 is not deenergized and the register PR restored to normal until the paragraphing is complete and the locking circuit 84, 168, is broken at contacts 163 of relay 148 (Fig. 3). It will be observed that the locking circuit 94 is normally completed by way of loop 168 (Figs. 1, 6 and 3), normally closed by back contact 163^a on paragraph relay 148 and back contact 176 of relay 170. 163^a being opened and 163 closed when 148 is energized the control of circuit 94 is transferred from 195 of *lm* to contacts 163 of 148, for 163 is well opened before 163^a is closed.

Subscribing.

Subscribing is accomplished in a manner similar to paragraphing. The subscript key SUB (Fig. 3) is pressed with the result that traverse register device Tr is energized over conductors 169 and 76, and the subscripture relay 170 is energized over conductor 171. Relay 170 thru contact 172 closes a locking circuit 173 for itself, which locking circuit extends thru normally closed contacts 174 in switch ES' of the initialing device IM, Fig. 3. Upon the final step of this switch, the switch arm 175 engages and opens contacts 174, thus unlocking relay 170. Before this however, both the subscripture and the initialing will have been completed as will be seen.

By its contacts 176, relay 170 closes locking circuit 168, 94, etc. of the register, disabling relay 62 as previously traced in connection with the paragraph relay 148, contact 176 transferring the contact from the limit switch *lm* to subscripture relay 170 as did contact 163 of relay 148. By its contact 178 it puts battery NB on conductor 179 which parallels conductor 155 (Figs. 3, 6 and 1) to normally open contacts 180 on left border switch *lm*, thence by conductor 181 (Figs. 1 and 6) to subscripture magnet 182, associated with shaft 152 in the same manner, and functioning in the same way as paragraph magnet 158 just described, with the exception that the subscripture magnet 182 oscillates shaft 152 in the opposite direction from magnet 158 carrying stop 160 and contacts 167 out of the path of shaft *s* of the carriage and stop 161 and contacts 165 into the path thereof. Thus when the subscripture magnet 182 is energized after traverse of the carriage C to the left border, the carriage is released for movement past, paragraph position to the subscripture position defined by stop 161. On account of lack of space these stops are shown at the right of the carriage C, but acting as they do upon movement of the carriage to the left, they would be in practice located to the left. Magnet 182 locks up by 182^a, 182^b to 164 but

when stop 161 is engaged contacts 165 are also engaged and opened, breaking the locking circuit 164, 168, 94, of register control relay 62 (Fig. 2) and also deenergizing magnet 182. Thereupon shaft 152 returns to normal and dictation may be proceeded with.

Relay 170 by contacts 114, previously mentioned, shifts circuit 110 of the period relay 116 to conductor 183 which connects with 10 conductor 76 of the traverse register. This is of no immediate effect since circuit 110 is open at relay 108, (Fig. 1) the relay 170 not having been pulled up until after the printing of the last period.

15 By contact 184 or relay 170 a conductor 110 is connected to branch conductor 185 leading to a relay 186 and to battery.

By contact 187 battery NB is put upon conductor 188, open normally upon contact 20 189 of relay 186 and by 190, 190^a, 191 to magnet 192 of ES'.

The operation is as follows; Upon the initial pressing of the key SUBS, the relay 170 is pulled up over conductor 171 and at 25 the same time traverse registered over conductor 76. Traverse to left border ensues. Switch *lm* then stops traverse, and at contacts 180 closes the circuit of magnet 182 which results in release of carriage C to subscript position, as described. Thereupon magnet 182 is energized, and locking circuit 164, 168, 94 of relay 62 broken. Bell 99 having sounded, the subscript is dictated. Since caps for the first letter automatically 30 follows a period, the first letter is a capital. A comma is dictated following the subscript as usual. The comma relay 140 closes circuits 110 to battery NB. This results in energizing relay 186, over conductor 185 and 35 also in registering traverse over conductors 188 and 76. Relay 186 locks up over conductor 186^a, thru contacts 174 of switch ES', (Fig. 3) along with conductor 173 of relay 170. Traverse ensuing, switch *lm* this time 40 closes the starting circuit 188, 189, 190, 190^a, 191 to magnet 192 of device ES', Fig. 3, circuit 181 having been broken at contacts 181^a of relay 186. Switch ES', stepping, prints the initials in caps as subsequently 45 described, and upon the last step thereof locking circuit 186^a of relay 186 and locking circuit 173 of relay 170 are broken. Switch ES' automatically stops itself and is thereupon ready to be started again. During 50 this period the initials of the dictator are printed in capital letters, for after each capital comes a period which results in automatically setting up caps again.

60 Paper feeding.

Just after the printing of the last period of the initials, switch ES' may close the circuit of the paper feed magnet, whereby paper feed to the next position is automatic, 65 however, this may be accomplished by hand

as follows; the FEED key of Fig. 3 closes circuit 194 of the FEED register at the extreme right of Fig. 3, and this register closes the circuit 195 (Figs. 3, 6 and 1) of the feed relay 196 of the pair 196, 197. 70

This relay thru armature 198 closes circuit 199 of the paper feed motor Pf. This motor rolls the platen thru gears *g* and feeds this paper until a perforation *p* permits brush *b* (Fig. 1, left) to close circuit 200 75 of the relay 197, which rocks armature 198 the other way and opens circuit 199 of motor Pf. (Any suitable braking means or circuits may be employed with the motor Pf, as indeed with any other motor of the system). Perforation *P* marks the headline of a new sheet, and in feeding to this position the foot perforation *p'* of the written sheet has been passed over, but since this 80 controls circuit 201 in parallel with circuit 198 of relay 196, the feed is not stopped until the headline of the new sheet is reached.

In cases where there are more sheets than one and the first sheet is filled completely, 85 perforation *p'* comes into play thru *b'* and 201 to automatically start the feed motor Pf for feeding to the next sheet, whereon the motor Pf is stopped thru perforation *p* as just described. This feed may be manually brought about at the end of any writing irrespective of subscripture, etc. 95

Line feeding.

If the amount of feeding desired be less 100 than the remainder of a sheet, the line feed key LINE may be pressed in rapid succession to feed the paper the desired distance. This acts thru conductor 142 and the LINE register D to close the circuit of magnet 105 Lf over conductor 143. As in case of actuating magnets Am and all other devices actuated thru register PR, the magnet Lf is intended to actuate suitable contacts functioning on contacts *bs* to step distributing switch *ds*. 110

Initiating addresses on plural numbers of pages.

This is accomplished thru the secondary 115 register SR, Fig. 2. Upon this register are registered the capital letters of the first line of the code writing on the first page only. This first line in a letter is the name of the addressee. When the paper is stopped at 120 the beginning of a sheet by energization of magnet 197 over circuit 200, magnet 202 in circuit 200 partially closes series circuit 203, putting battery on registers D of the secondary register SR. This circuit 203 is completed at contacts 203^a by the energization 125 of caps shift magnet Ca, and thru segmental contacts *k*, *g* on page numbering switch Ps. These contacts are closed (see Fig. 23). When switch PS is at normal or first page 130

position only. At other positions the arm 210 having moved away they are open. Therefore the secondary register SR is energizable only on the first line of the first page for the registration of capital letters only, the series circuit 203 being closed each time the caps magnet Cs is energized. Thus the first letter of each name of the address is registered, one on each trunk t' to t^s in succession. The circuits 205 of registers D of secondary register SR are connected in multiple with the devices D of the primary register PR to circuits 14 at points 206. Also conductors 15 of the letter actuating magnets w' are multiplied to contacts P—O⁴ of SR. There is a device D in the secondary register SR for each device D of a letter character in the primary register PR. Thereby any letter character whatsoever may be registered on register SR.

Distributing device DD² and actuating switch DS² act in the same relation as trunks t^5 to t^8 as does distributing device DD and switch ds of trunks t' to t^4 , but switch DS² acts only upon the first line of pages succeeding the first. This is brought about in the following manner:

The armature 202^a of relay 202^b (Fig. 1) when relay 197 is energized over circuit 200 momentarily closes on its up-stroke (but not thereafter on its down stroke) contacts 207, of circuits 208, thus putting battery on stepping magnet 209 of switch DS², thru now closed contacts 210, 211 of page numberer PS. Relay 197 is energized only at the beginning of a page. Contacts 210, 211 are closed only after switch PS makes one step. Thus at the top of the second and succeeding pages switch DS² is started, but not on page No. 1. Started it closes by switch arm 212, arcuate contact 213 in circuit with constantly rotating interrupter In, which results in stepping switch DS² once for each revolution as well known in this type of stepping switch. Thus one by one trunks t^5 to t^8 are connected to battery and the actuating magnets w' are energized to print the initials registered on register SR.

Alternating with contacts 214 connected respectively with trunks t^5 to t^8 are contacts 215 connected commonly to conductor 216 which leads to the period actuating circuit 101 of Fig. 1. Thus switch DS² in its stepping alternates the printing of periods with the initials of the addressee as should be.

After the last period the arm 212 of switch DS² steps off of the arcuate contact 213, thereby automatically breaking the circuit of its stepping magnet 209 until closed again at the beginning of a succeeding page. Switch DS² is shown as provided with two sets of contacts 214, 215, 213 in multiple and alternately used. Multiple steps may be similarly provided in any switches.

55 The devices D of secondary register SR

are not released as the characters are printed as in case of devices D of register PR, but are retained in actuated positions until the final page is written, as will hereinafter appear.

70

Page numbering.

The page numbering switch PS (Fig. 2) is associated thru contacts 217 with the circuits of a series of registers (2) (3), etc., 75 in register SR. Normally its arm 210 rests free from contacts 217. Whenever relay 196 (Fig. 1) is energized to shift a new sheet, however, relay 201^a (Fig. 1) closes circuit 218 of stepping magnet 219, thus stepping switch PS one step over the first contact 217 and to a point between No. 1 and No. 2, whereupon devices (2) (3), etc. being permanently connected to common conductor 220, the first one of the series, to wit: (2) 85 is energized. Switch PS is retained in this position (shown in dotted lines Fig. 2) between contacts 217 by holding pawl 221 against the tension of a spring 222, drawing it toward normal, upon the last page of a 90 writing, however the pawl 221 is withdrawn by magnet 223 which is energized and retained energized when the subscripture key has been pressed, until the head of a new sheet has been reached. This is accomplished by a locking circuit 224 for the release magnet 223, which locking circuit 224 is closed thru normally closed contacts 225 in relay 226, energized on the first line of the first page from control conductor 203 of 100 register SR. The initial closure of circuit 227 of relay 223 is accomplished directly from the subscripture key SUB (Fig. 3) by contacts 227^a connecting to NB.

The next to the last contact 214 of each bank of switch DS² is connected not with a trunk t^5 to t^8 but with a special trunk st connected commonly with contacts 100 of devices (2) (3), etc. which are connected with numeral trunks 101 in parallel with contacts 110 100 of register PR. Thereby after the last initial of the addressee is printed the page number, 2, 3, or 4, as the case may be, is printed.

Simultaneously with closure of the period 115 circuit following this arm 212 closes by contact 228 release circuit 229 of release magnet mo of the number registers (2) (3). Thus each register device of group (2) (3) is released soon after the page number registered 120 has been printed, whereby upon the operation of switch DS² upon succeeding pages, the numbering is appropriate.

The timing and the distance of the steps of switches DS² and PS may be made anything desirable or suitable to meet operating conditions. Both of these types of switches are well known in the art of telephony and telegraphy.

125 The release of the letter registers by mag- 130

net *om* is effected in conjunction with release of page numbering switch PS over the same circuits, the circuit 230 of release magnet *om* being connected in parallel to the circuit 227. Release circuit 231 to release magnet 232 distributing device DD² is also closed in parallel with 227. Device DD², unlike DD is returned to a determinate normal by a spring 233, as in case of cams *c'* in the devices (2) (3), and the absence of a multiple number of contacts, there being provided only one pair 100 in each case associated with the common special trunk *st*.

When the release circuit 239 is closed by switch DS², there is closed from the same contact 228 the starting circuit 236 (Figs. 1 and 6) of the dating mechanism DA (Fig. 6). Stepping magnet 237 is in circuit 236, and upon this momentary energization steps switch ES one step whereupon it continues stepping of itself by virtue of the closure by arm 238 and arcuate to contact 239 of the circuit 240 of magnet 237, upon continuously rotating interrupter *In* or the equivalent. Switch ES thus steps until it again slips off the arcuate contact 239 whereupon the circuit 240 is broken.

During the stepping switch ES closes successively thru arm 238 and contacts 241 of its banks (of which there are two shown as in case of switch DS², the number of such banks being merely a matter of convenient relation of the length of the step of the switch to the number of the steps) the circuits of trunk *ns*, which are connected respectively with arm 242 of number switches *Ns*. These arms, as previously described, may be swept over contacts 1, 2, 3, etc., up to 10. Contacts 1, 2, 3, etc. are connected in multiple to conductors *d'* to *d⁹* and *d⁰* which are connected to actuating magnets *w²* (Fig. 1) in multiple with conductors 101 of the figure register circuits. Thus as switch ES steps the circuits of six (or a less number) actuating magnets are successively closed. The particular circuits closed depends upon the setting of arms 242 of switches *Ns*. As shown beginning with switch *Ns* on the left, the arms 242 rest on the following buttons (off), 2, (off), 6, 1 and 3, this actuating in succession magnets *w²* to print 2613. However between each successive pair of contacts 241 are contacts 243, connected commonly to a special conductor 244 leading to the hyphen or dash printing magnet *w'*. Thus a hyphen is printed between each pair of numerals represented by switches *NS*. Thus the 2613 above referred to would be printed as 2/6/13, representing the date of February 6, 1913. So by appropriately setting arms 242 any date whatsoever may be printed. Thus for date of Dec. 29, 1913, the arm 242 of the first switch *Ns* (from the left) will be set at the first button, the second at button 2, the third at button 2, the

fourth at button 9, the fifth at button 1, and the sixth at button 3. Switch ES will effect the printing of these numerals in the following form; 12/29/13.

During the time of printing of these numerals the circuit of the figure shift magnet F₈ is closed thru arm 238 and contact 239 over circuit 245, 130 branching from 240. At the ninth step of switch ES it passes over contact 246 and onto the blank space 75 246^a putting battery NB on contact 246 and conductor 247, which conductor leads to conductor 76 (Fig. 3) connected with the traverse register TRAV. Thereby traverse of the carriage C to the left border is registered and ensues as previously described.

When stepping magnet 237 of switch ES is first energized over circuit 236 (DS² may make a special final step for this before stopping), a circuit 250 may be closed to subscripture magnet 182, thru normally closed contacts 165' thus resulting in a removal of the date from the initialling and page numbering to a point near the right border of the page, for the energization of 90 the subscripture magnet 182 results in immediate shift of the carriage to that position. If desired additional contacts may be provided in connection with 165 to initially close the circuit of 237 (as shown in Figure 20) and direct connection of 236 with 237 omitted, or else switch ES may be given one or more false steps to allow time for the complete shifting of carriage C to subscripture position before the printing of the 100 date.

The initialling of the dictator.

Reverting now to the subscripture relay 170 (Fig. 3) it will be seen that when this relay is energized it closes conductor 110 from the comma relay (Fig. 1) upon conductors 183 and 185. Conductor 183 energizes the traverse register TRAV thru its connection with conductor 76, while conductor 185 energizes relay 186, which locks up by conductor 190^b (Figs. 3 and 6), thru normally closed contacts 172. Traverse after the subscripture having ensued, circuit 190 preliminarily closed by contacts 189 of relay 186 is completed by contacts 190^a of limit switch *lm* (Figs. 3, 6, 1 and 6) thereby energizing magnet 192 and stepping switch ES' its initial step, thereafter it steps of itself by reason of the closing of the circuit of 192 thru arm 175 and arcuate contacts 254. Thus it carries its contact arm 175 step by step over contacts 255, connected to trunks *is* leading to the arms 256 of switches *Is* of the initialling mechanism *Im*. The arms 256 of switches *Is* are each associated with 26 buttons connected respectively in multiple with 26 conductors *n'* to *n²⁶* leading each to an actuating magnet *w'*. By setting the arms 256 to desired buttons any 130

desired set of initials whatsoever may be printed. They are all printed in capitals because of the energization of the caps magnet Cs by conductors 257 and 22 from 5 arm 175 and arcuate contact 254.

- Preferably there are provided alternating with contacts 255 contacts 258 which are connected commonly to conductor 259 in multiple with conductor 244 leading to the 10 hyphen, dash or period magnet of the group w' or w^2 . Obviously the printing of the initials will be then after this fashion C/S/W, or C—S—W. The punctuation may be omitted if desired. When switch 15 ES reaches its last step, arm 175 is stepped off contact 254 and the switch stops in this position temporarily, opening locking contact 174 and releasing the subscripture relays 170 and 186.
- 20 Simultaneously switch ES' closes momentarily the contacts 260 closing thus the circuit 261, connecting with conductor 195 leading to paper feed magnet 196 and thus bringing about an automatic feeding of the paper 25 to the beginning of the next sheet. Also the circuit 262, 247, 76 of the traverse register is closed bringing about an automatic traverse to the beginning of a new line.

30 *Composition writing.*

With the above description of the details of the system by which the method of my invention is carried out, the high efficiency and the economy in the operation of my invention will be readily apprehended and appreciated. The operation will be described with particular reference to a composition, one or more pages in length, which letter may be but one of several hundred compositions 40 of the same size and type which may in the aggregate constitute a day's work.

Coming to the machine the operator closes the switches 270 and 271 (if the same have not already been closed), thus starting up 45 the motor generator set MG and placing power therefrom from buses NB and PB. Pressing the caps key CAPS (Fig. 3) he signals into the transmitter T' (Fig. 4) the signal titles of the party addressed. Assume 50 that this is Mr., as usual. The first letter "M" is recorded as a capital, whereupon carriage C is released from the position in which it was placed thru the pressure of caps key Ca, and the next letter is written in small type. Now pressing the figure key FIGS. of Fig. 3, the word "period" is signaled 55 into transmitter T', resulting in the recording of a period thru the energization of a plurality of registers of the group PR closing the circuit 101 of the period actuating magnet. Each of these keys CAPS and FIGS are but momentarily pressed. The first name of the addressee is signaled in quick succession, and printed with its first 60 letter a capital by reason of the fact that a

period and a space followed the signal of the title. Pressing the caps key CAPS, the last name is then signaled, and again pressing the Figures key FIGS, the word "comma" is signaled, resulting in the placing of a 70 comma after the fully written name of the addressee. This requires but four acts upon the part of the operator, (beside the operatives of signaling) pressing caps and figure key alternately in ready succession twice. 75

In the act of recording the comma, the circuit of dating magnet 237 and subscripture magnet 182 are closed by magnet 140 in the circuit of the comma actuating magnet w^2 (thru contact 141^a and contact of relay 140^a 80 closed only when 208 is energized by 202 on the first line), resulting in the immediate shifting of the carriage C to the left to the subscripture position defined by stop 161. At this point switch ES records at the right 85 hand side of the top line of the sheet the date which is set up upon the switches Ns. At the end of the dating operation switch ES closes the circuit of the traversing register TR over conductor 247, whereupon the carriage is traversed to the right. The address is immediately signaled and recorded. Commas do not now energize 237 for the first line is passed and 202 is energized. The figures key is pressed whenever a punctuation mark is signaled and the caps key CAPS is pressed just before signal groups not following a period and which it is desired to commence with a capital letter. 95

Pressing the paragraph key PAR, the carriage C is first traversed to the extreme right again and then released by the energization of magnet 158 (Fig. 6) for travel to the paragraph position, whereupon signaling may proceed with the same rapidity emphasis of the syllables sub-groups being made perhaps slightly greater than is usual in word dictation, and the time interval between syllables being made slightly longer. The essential point in the operation is that 100 the emphasis of spaces between signal groups shall be made greater than the emphasis of syllables thereof thru the permitted lapse of a longer time interval. With a few hours 105 practice one can readily familiarize himself with this little peculiarity in signaling. Whenever punctuation marks or other figure characters are to be recorded the figure key FIGS is momentarily pressed, just in advance of the signaling of the mark. After 110 periods, a capital letter for the first word of the following sentence is set up automatically. At other times the operator has only momentarily to press the caps key CAPS as heretofore indicated. At the end of a line 115 traverse takes place automatically, and automatic differentiation is made by the spacing mechanism SM between syllables and spaces, with the result that syllables are properly marked by dashes. There is no confusion 120

125 130

or misdivision of syllables at the ends of lines, for the reason that traverse ensues only upon the occurrence of a syllable, a space, or a figure character.

Whenever a paragraph is desired, the operator has only momentarily to press the paragraph key PAR, and upon the shift of the carriage C to resume signaling. Upon the registry or commencement of each carriage shifting movement, bell 96 (Fig. 2) is tapped, warning the operator to cease signaling until the movement is completed. At the end of the first page of the signaling, the proper feed to the next page follows automatically by reason of the engagement of brush b' thru perforation p' with contact t. This results in the energization of the paper feed motor Pf, and the engagement of contacts b thru perforation p results in stopping the feed at the first line of a new sheet. Immediately the initials of the addressee, which were registered upon the auxiliary register SR in the dictation of the name on the first line of the first sheet are recorded by the operation of the secondary distributing switch DS², the operation of which is initiated over conductor 208. Following this the number of the page is also recorded by the operation of the same switch DS², and at the end of its operation switch DS² closes the circuit 236 of the dating device DA, resulting in the stepping of switch ES to record the date. Thereafter the circuit of traverse register TR (Fig. 3) is closed over conductor 247 and traverse of the carriage C to the extreme right ensues, and dictation may be commenced on the new sheet. This operation of shifting to a new sheet, and recording the proper data upon the head thereof, takes but a fraction of the time now required for the manual change of sheet and manual record of the heading.

Upon the completion of the dictation one subscripture key SUBS is pressed, resulting as previously set forth, first, in traverse of the carriage to the extreme right, and then thru the energization of subscripture magnet 182 in its release to the subscripture position, at which point the subscripture may be signaled, the caps key CAPS being momentarily pressed just in advance to capitalize the first letter, and the figures key FIGS being pressed just before signaling the usual following comma. Upon the record of the comma after the pressure of the subscripture key, traverse of the carriage to the extreme right takes place, and upon the completion thereof of the initialing mechanism IM is automatically set in operation, whereupon the initialing of the dictating party as indicated by the set of the switches Is are recorded on the extreme left margin as usual. Upon the record of the last period, dash, or the like, following the last initial, the feed of the paper to the next sheet follows auto-

matically by reason of the closure of circuit 261, 195 at contacts 260.

Thereupon a second letter or other writing may be immediately commanded, or else the already written letter may be severed from the individual sheet and the machine left at rest.

Obviously, in this use of the machine, the operator need give practically no thought to the manipulation of the machine, but may confine his attention wholly to the dictation. Only an occasional pressure of the caps or figures key is normally required, and a still less frequent use of the paragraph key PAR. It is my purpose to have these keys mounted on a disk plate, or a handle which may be operated in one hand, and to connect them by a cable with the machine which may be located at some suitably fixed point beside or near the operator's desk. Then when the transmitter T' is made portable as in the form of the usual head set used in telephone exchange systems, or the usual desk telephone sets commonly used in offices, the operator may have entire freedom of movement, and in the ordinary course of code signals the free use of both hands for handling papers under consideration at the time or for making any desired notes, etc. Moreover, when used by business men in offices, the room for the machine proper need not be provided on already over-crowded desks, but instead sufficient room only for the transmitter and control keys, the machine proper being mounted on a suitable portable stand as in case of the well known adding machine, and placed beside the desk, or in some corner out of the way.

The method of my invention is obviously capable of being carried out by a wide variety of modifications, many of which may be devised by those skilled in the art without departing in any way from the spirit of my invention. I desire to cover in the annexed claims all such modifications, and in connection with the foregoing principal form of my invention I have shown several such modifications.

The first of these is found in Fig. 13. In this figure is illustrated a substitute form of the register PR. Instead of using devices comprising a single actuating magnet rm, and a plurality of sets of contacts o' to o⁴, successively drawn into and out of action by cams e' and e², in this modification I make use of a plurality of sets of contacts e' to e⁴, each controlled by an individual relay rm', rm², rm³ or rm⁴, as the case may be. There is provided a set of the relays rm' to rm⁴ for each pair of conductors 14, 15, which relays are all commonly energizable from conductors 14. That one of them which is energized upon a given energization of conductor 14 is determined by the position of switch arm 300 of distributing switch DD'

which in this modification performs the functions of the distributing devices DD of Fig. 2. All of the relays rm' are connected in multiple to conductor 301 controlled from contact 301^c of switch DD', all of relays rm^2 from common conductor 302 and contact 302^c, etc. Hence that one of the relays of any set rm' to rm^4 is energized which is connected to that one of the conductors 301 to 304 which the switch DD' has at the time connected to battery, as indicated. Assuming this to have been relay rm' of the extreme left hand group, upon pulling up, this relay locks up by way of double locking contacts 305, 306, and just before making the latter contact, breaks contact 307 by which it was connected to conductor 14. Contacts 305 and 306 connect with battery respectively by way of conductors 308 and 309, the one connecting therewith thru locking switch LS' of the step-by-step type and the other by bank *ds'* of LS' to common battery conductor 310 to negative side of battery. Additionally, relay rm' closes by front contact 311 the connection of conductor 15 to trunk t' of the group t' to t^4 which are individually multiplied to contacts 311 of the corresponding relays rm' rm^2 , etc., as the case may be. Still further, relay rm' closes by contact 312 loop 313 which connects a timing 314 from conductor 14 to battery, as indicated.

Over conductor 15, the actuating magnet of the represented letter is energized, and timing magnet 314 by contacts 315 closes loop 316 common to all the relay sets rm' to rm^4 and thereby energizes relay 317. This relay pulling up by front contact 318 puts battery on conductor 319 and by way of back contact 320 of shifting relay 321, and conductor 322 upon stepping magnet 323 of distributing switch DD', whereupon this switch makes one step. The spacing of contacts 301^c to 304^c is made such that one step of the switch carries arm 300 one half the space between adjacent contacts, whereby in the case illustrated, the arm 300 is stepped off the contact 301^c to a point beyond contact 301^c and contact 302^c. Relay 323 by contact 324 closes the circuit of relay 321 by way of conductor 325 and front contact 326 of relay 317, whereupon relay 321 pulls up and breaks circuit 319, 322 of magnet 323 at contact 320 whereupon a locking circuit for magnet 321 is established at the make-before-break contact 324' of the pair 324, 324', this locking circuit extending thru contact 326 on relay 321.

This condition pertains until timing relay 314 is deenergized, and this relay is not deenergized until conductor 14 is deenergized, relay 314 releases contact 315, and hence opens the circuit of relay 317 which in falling back again closes the circuit of stepping magnet 323, this time by back con-

tact 327, conductor 328, front contact 329 of relay 321 and conductor 322. Switch DD' takes another step which this time brings it upon contact 302^c, and magnet 323 in pulling up in addition to stepping the switch opens locking circuit 324', 326 at contact 324', whereupon relay 321 is deenergized, and opens the circuit 328, 329 of magnet 323 at contact 329. All of these magnets are made extremely quick acting, so that but 75 a fraction of a second is required for this entire operation, a period less than the shortest period of energization of any conductor 14. By means of this cycle of operation, it will be seen that immediately any relay 80 of any set rm' to rm^4 is energized, and the conductor 15 connected to the proper one of the trunks t' to t^4 (commonly designated 309) switch DD' removes battery from the corresponding one of the common conductors 85 301 to 304, and immediately upon the deenergization of conductor 14, battery is placed upon the next one of the common conductors 301 to 304. The result is that no matter how rapid the signaling, not only is the 90 energization of successive conductors 14 prevented from connecting a plurality of conductors 15 with the same one of the trunks t' to t^4 , but prolonged energization of the conductor 14 does not result in connecting 95 one conductor 15 to two trunks t' to t^4 . Moreover, immediately succeeding the second energization of the same conductor 14 results not in connection with the same trunk or with two trunks of the group t' to t^4 , but 100 each time with a different trunk, whereby double code letters occurring in any given code word, and especially at the division into syllables, may be recorded. In short, the cycle of operation of switch DD' by 105 means of the timing relays 314 eliminates all possibility of confusion.

The operation of the device for all of the other relays of the sets rm' to rm^4 is the same for each relay of each set as it is for 110 the relay rm' of the extreme left hand set illustrated as just described. If before record is made of the character designated by the energization of the relay rm' of any set, the corresponding conductor 14 is deenergized and another energized, this next energization will result in the operation of relay rm^2 of the corresponding set, since at this time switch DD' has put battery upon common conductor 302. The same is true 120 as respects a successive energization of relays rm^3 and rm^4 of the sets.

New trunks t' to t^4 , as in the case of the form of Fig. 2, are connected to contacts on a distributing switch *ds''* operated by a 125 stepping magnet *sm'* over conductor 21 which is connected to battery by switches *bs* in a manner entirely similar to the connection of switch *ds* of Fig. 1. There is this difference, however, that instead of 130

operating release devices RD by gearing connection gs , switch ds'' in this instance is connected by the shaft 330 with locking switch LS'. The switch arm 331, or the contacts thereof, are of such angular extent that they cover the contacts 308^c of all but one of the locking conductors 308 at the same time. Thus all but one of the trunks t' to t^4 may be in use at the same time, but as the distributing switch ds'' puts battery onto the trunks to energize the actuating magnets w' and w^2 the locking switch LS' successively releases the next succeeding relay of the sets, functionally in the same manner as does the rotating cam release device RD.

It will be observed that I have shown all of the step-by-step switches in this form as in the double ended arm and semi-circular bank type, but this showing is conventional only, as any other type of step-by-step switch may be used as well.

On the right hand of Fig. 13 is indicated by a single set rm' to rm^4 , a similar register device PR² which is intended to take the registration of all traversing movements of the carriage C and all feeding movements.

Normally this register PR² is not operated but whenever a traversing or feeding movement of carriage C is initiated, and relay 62' of Fig. 13 is pulled up over conductor 61 it can be traced thru Fig. 1, etc., to the various traversing element controls as aforesaid. Only upon the completion of the traversing movement set up is the locking circuit 94 broken as hereinbefore fully set forth. By this means whenever 62' is energized battery is removed from arm 300' of DD' of register PR² whereby further registrations on PR' are precluded just as in the form of Fig. 3. DD' has connected with it however, a synchronously stepped switch DD'' controlling the secondary register PR² exclusively. This continues in operation carrying out the sequential registration of the traversing movements as before. The moment the traversing movements cease 94 is broken, 62' is deenergized, and the switch DD' and the primary registers PR' are restored to normal operation.

ds'' and LS' operate the trunks t' to t^4 of PR' and PR² jointly. It will be noted that 62 and 62' take care of "end of line" traverse movements. The inter line movements are cared for by a lockout in connection with the control keys hereinafter to be described.

It is entirely feasible to construct a type-writing machine for an extremely high speed of operation, though the attainment of this speed may be at the expense of durability. With such machines, however, the registers PR will not be needed, since the machine will record the characters as fast as they are pronounced. The modification of Fig. 14 is devised particularly for use in

connection with such a machine. As in case of Fig. 13, the apparatus here shown is intended to take the place of that shown in Fig. 3. The circuits 14 instead of operating primary register magnets Rm, connect directly in most cases and indirectly thru normally closed contacts in other cases, with conductor 14 whereby actuating magnets w' are actuated directly by relays Re, or it may be directly from coherers co or the equivalent. These conductors 14 which do not connect directly with conductors 15, connect thru shifting contacts 335 commonly separable by relay 336 to shift the connection from one conductor 15 to another. This is to provide for alternative spelling, or in other words for the proper spelling of those words which have the same pronunciation. For instance the word "read" which may also be spelled "reed". The conductor 14 energized in response to the "e" sound or the second of two successively responsive to the "ee" sound, in order to effect the record of the word "read", must be connected to the conductor 15 controlling the circuit of the actuating magnet w' of the letter "a". Thus, in the normal operation, the word recorded would be "reed", but when it is desired to record the word "read", the key SPEL is pressed, energizing relay 336, and resulting in the shifting of all the contacts 335 and the connection of the proper conductor 14 to the proper conductor 15 to record "a" instead of "e" in the third place. Obviously many modifications of this idea may be used, the shift contacts 335 being divided into groups, each controllable by a separate relay 336 from a separate key SPEL, if the rules of spelling adopted make it advisable.

To record figure characters from dictation in the absence of the register device PR, a set of locking relays 337 is provided, these relays being each energized from conductor 14 with which it is associated and by common conductor 338 to battery thru the figures key FIGS, which is closed and held closed when it is desired to record figure characters. Each relay when it pulls up closes a locking circuit for itself by contacts 339 to common locking conductor 340 normally closed to battery thru contacts bs' in series, the contacts bs' being each pair individual to a type bar B of the machine and actuated by cores c of actuating magnets w' , w^2 in the same manner as are the switches bs . The pulling up of a series of 337 closes by contacts 341 of the relays in series one or another of the circuits 10 of the figure character actuating magnets w^2 . That one closed depends upon the particular combination of relays 337 which is pulled up. Thus for instance, to represent the period character, those relays 337 connected respectively with conductors 15 connected with the ac-

tuating elements of the characters *p*, *e* and *r* may be the ones chosen, and when the last one of the three pulls up, the circuit 101 of the period magnet is closed. These circuits are not claimed in detail, since many combinations may be used but a number of them are shown in detail. Promptly upon the record of the figure character so determined, contacts *bs'* are opened as the corresponding magnet *w*² is energized, and the relays 337 are locked and fall back. In indicating successive figure characters, such for instance as numerals, the operator should wait until he hears the character struck before he dictates the next succeeding, so that the relays combining to determine the record of the next character may not be unlocked prematurely. Preferably contacts *bs'* are opened, unlocking relays approximately at the extreme upper end of the stroke of the type bar. Figs. key controls also the same lock out circuits as before (not now shown).

Not only may the peculiar form of the register devices made use of be varied, but the form of the "vocal analyzer", or other speech operated controller may also be widely varied. In Fig. 6 I have shown a modification of this in which instead of utilizing tuned circuits, I make use of a diaphragm *Di* upon which the sounds are directed. This diaphragm is pivoted at its center 342 instead of being supported at its outer edge, and in operation vibrates on various diameters forming the well known chords of Chiadni. The outer edge of the disc is provided with radial slits or slots 343 forming a plurality of more or less rigid spring fingers 344 which are thrown into forced vibration of greater extent than the vibration of the main body of the disk. Each of these fingers in vibration is arranged to close a particular circuit *se* of a relay *Re*. The pronounced sounds are thus in effect split up into their various components and each component effects the energization of a particular relay *Re*. In constructing an analyzer of this type there is necessary, of course, an adjustment of the contacts 345 each to the proper finger 344 to obtain proper differentiation. This can be readily determined by experiment, a particular finger of a particular plurality of fingers being set in highest vibration by a particular sound only. The fingers 344 may be tuned if desired, as in case of the Frahm frequency indicator being for this purpose made of not only more or less mass, but being made of greater or less length and tension.

In Figs. 9 to 12 I show several apparatuses for making use of this diaphragm analyzer *Di*. In the first of these, shown in Fig. 9, the diaphragm *Di* is supported rigidly at the front end of a screw 346

mounted adjustably in arm 347 of bracket 348 carried on pedestal 349. Also carried on the bracket 348 in a plane parallel to that of diaphragm *Di* is a contact ring 350 of insulating material thru which project adjustable contacts 345 in close proximity to the back face of the diaphragm. Housing the diaphragm closely but not touching the same and extending in front thereof is a housing 352 into the center of which is let a mouth piece 353 of the usual type found in telephone transmitters. Upon speaking into the mouth piece the air in the interior of the housing 352 is set into vibration and the diaphragm vibrated correspondingly, with the result that the contacts 345 are closed in succession, singly or in combination.

Another form of this device is shown in Fig. 12. Similar parts bear similar reference numerals. The diaphragm in this form is hollow in the center, being formed of two disks sealed together at their outer edges adjacent the inner ends of fingers 344 after the fashion of a well known aneroid barometer. It is supported on the outer end of a rigid tube 354 which communicates with the interior. The interior contains a fluid, compressible or non-compressible, the pressure of which—and hence the tension of the diaphragm—may be regulated by turning piston screw 355 threaded into the outer end of the tube 354. Tube 354 is supported directly in arm 347, being splined therein by key 356. It is adjustable by means of screw 357 in bracket 347 bearing against collar 358 and adapted to force collar 358 and tube 354 forward against the pressure of spiral spring 359 intermediate the collar 358 and the insulating ring 350. By this adjustment as with the adjustment of screw 346, the diaphragm may be adjusted minutely with respect to contacts 345. This adjustment of the diaphragm as a whole, when employed with the adjustment of the individual contacts 345, makes possible adjustment to meet any existing relative vibrational conditions as respects the various portions of the circumference of the disk.

In Fig. 10 is shown still another form, in which, instead of using the diaphragm, a parabolic bell 360 of this steel or other material having the proper vibrational qualities is made use of. The bell is adjustably supported from arm 347 as in case of the diaphragm, and its outer edge is slit or slotted to form fingers 344 lying approximately parallel with the axis of the bell. Contacts 345 are supported by ring 361 in a plane transversely of the axis of the bell, and housing 352 is supported directly from ring 361. The vibration in this form of analyzer is highly intensified, owing to the parabolic shape of the vibrating element, the vibration taking place on diameters per-

pendicular to the axis of the bell. If desired, the mouthpiece 352 may be extended inwardly, as shown in dotted lines, to a position approximately at the focus of the 5 parabolical surface of the bell.

It has been heretofore mentioned that in the embodiment of this system in a typewriting machine, it was intended to feed the paper from a roll. In order to do this 10 satisfactorily, and economize space, it is highly desirable that the type basket move instead of the platen. In Figs. 15, 16 and 15 17 are shown the means by which this is carried out. 370 is the main frame of the machine. The platen 371 is supported in longitudinally fixed position in eccentric bearings 372. By the simultaneous movement of bearings 372 at both ends of the platen, or by other equivalent arrangement 20 such as is commonly known in the old Remington typewriters, the platen may be shifted up and down for capitalizing. The same upright 373 which supports the platen is extended to the rear and connects with 25 upright 374 to form a framework for supporting the paper rolls. Preferably all of the paper rolls are supported from arms which project rearwardly from the hindmost upright 374 whereby the rolls may be 30 removed and renewed readily. The roll 375 bearing the original sheets is supported from bracket 376 and feeds underneath the platen 371 and over table 377 and top roller 378 to basket 379 which catches the original 35 copy. The roll 380 for the copy also feeds under the platen, but after passing from the platen it passes to reel 381 supported from bracket 382, upon which reel it may be wound by hand or by mechanism driven 40 from the platen 371. Between the original and the second sheet rolls 375 and 380 pass a belt 384 of carbon paper or other duplicating material, this belt passing over the platen between the original and second 45 sheets, and over idler pulleys 385 and 386 in such position that it clears the rolls 380 and 381 of the second sheets.

In front of the uprights 373 and somewhat below the platen 371 is supported the 50 longitudinally movable frame 387 of the type basket 388. As clearly shown in Fig. 15 this frame is supported on ball bearings 389 in laterally extending race-ways 390. Any other equivalent means of support may 55 be used. This basket is formed by individual type bars 391 pivoted commonly upon a segment 392 in a plane approximately transversely of the machine, and having their heads 393 (see Fig. 17) in an arc shaped rest 394. Their inner ends are connected by links 395 commonly mounted on transverse axis 396 of bell cranks 397 commonly mounted on transverse axis 398 extending between the two branches 399 and 60 400 of the frame 397. The type bars are

normally biased against steps 401 by springs 402 or else held against rests 394 thereby. The ends 403 of bell cranks 397 lie closely adjacent to the front edges 404 of a series of transversely extending edgewise arranged 70 parallel actuating bars 405.

There are two sets of these actuating bars, one on each side of the center of the machine, as clearly shown in Fig. 15, each set carried in slots 406 in combs 407. Both the inner 75 and the outer end of each bar 405 are supported from bell cranks. The inner end 408 is connected by pin and slot connection 409 with the substantially parallel arm 410 of bell crank 411. The right angular arm 412 80 of bell crank 411 is connected by rod 413 with the similar arm 413 of bell crank 414 pivoted upon vertically extending axis on pintel 415 supported by bracket 416. Arm 417 of crank 415 connects with the corresponding end of bar 405, and is substantially parallel with the body of the bar. Electromagnet $w' w^2$ is enclosed in an aperture 418 in vertically extending iron block 419 and thru rod 420 connecting with arm 417, actuates 85 bar 405. It will be observed that owing to the substantially parallel relation of arms 417 and 408 and bar 405, and the connection 413, the movement of bar 404 upon actuation by magnet $w' w^2$ is a parallel, bodily, lateral 90 movement substantially free from endwise displacement and of the same extent from end to end of the bar. Thus no matter where the type basket 388 may be in its various positions, the arm 403 of any type bar 100 391 is always directly over its actuating bar 405 and in position to receive the proper actuating impulse therefrom.

The actuating magnets $w' w^2$ are arranged in banks in blocks 419, and the 105 blocks arranged in pairs as indicated, and as shown in Fig. 15, the centers 421 of the actuating magnets of adjacent banks are staggered with relation to each other, whereby magnets of substantial size may be used. 110 As shown the banks of the front set are approximately one-half diameter apart. Those of the rear bank will be disposed quarter diameter as respects those of the front set. Since there are provided banks 115 both right and left as well as front and rear, by the proper staggering of the connections to the bars B, there will be ample room for iron-clad electro-magnets of very substantial proportions.

It will be noted that the ends of bars 405 connected with the actuating magnets $w' w^2$, are slightly offset. This is done to accommodate the axis 415 of the bell cranks 414, whereby the approximately parallelism of 125 the arms 417 may be preserved.

For actuating the shiftable type basket 388, the usual actuating elements provided in connection with shiftable platens may be provided. Many such are well known and 130

it is therefore not needful that they be set forth here. It is preferable that they be arranged on the underside of the basket from 387 in any suitable manner, being appropriately connected with the main frame 370. I show, however, the spacing rack 422 connected with frame 387. Furthermore, I show a tabulating bar 423 mounted on the front of the main frame 370 in suitable bearings and carrying adjustable stops 424 arranged to be variously engaged by fixed stop 425 on the front of the shifting frame 387. This tabulating bar and its controllers may be in all respects similar to those now employed in connection with shifting platens, the essential element being that the shifting frame 387 takes the place of the shifting platen as the movable part.

It will be noted that the bar 405 is the equivalent of bar B of Fig. 5, and that the magnet 403 is for the purpose of operating the subscripture shift, the tabulating bar or rack serving the same purpose as the shift 152 of Fig. 6.

In conclusion a number of items need supplementary mention. First, the relay 31 of the modified analyzer circuits of Fig. 5 instead of being in a special tuned circuit as in Fig. 4 is in series with the common battery lead NB of the relays Re. The syllabic groups of current impulses in this common battery lead are separated by periods of time proportional to syllabic and space intervals. It is believed best that the relay 31 be made a trifle slow in operation so that intervals less than syllabic intervals between current impulses may not result in its falling back prematurely. The natural characteristics of the relay may be found entirely sufficient for this purpose. The same is true of the relay 31 of Fig. 18.

The resonant circuits *sc* may be of any known form, or forms to be known. At the present time there are known to the art many forms of these circuits for effecting operation of relays. Sometimes these circuits are called tuned selective circuits. Many of them are to be found in the art of wireless telegraphy and still others have been originated and published for use in connection with vocal typewriters or voice analyzing machines. Instead of the coherers *co* of the granular type, detectors of the mineral or other type may be employed in lieu thereof. The coherers *co* if of the form illustrated may be decohered in the usual manner by having any form of tapper actuated from a magnet in the train energized thru the coherer such for instance as corresponding magnet *rm* of device D. The criterion is that decoherence should not take place until that device whose actuation is sought is actuated, or else some device having control thereover is actuated. Tuning

involves merely mechanical and electrical skill.

In Fig. 3 both figures shift FIGS and cap shift CAPS have been shown and in Figs. 3, 6 and 1 their connection thru a system of circuits to figures and caps actuating magnets *Fs* and *Cs* respectively. Obviously one or the other of these shifts may be omitted depending upon the character of the typewriting machine which is used. Most of the modern machines are provided with caps shift only. This suggested omission applies of course to carriage shifting movements only. In order to secure the imprint of dictated figure characters, a key the equivalent of the FIGS key of Fig. 3 and having the same functional control needs be used. Specifically then let us assume that *Cs* and *Fs* of Fig. 1 impart to the carriage the same shifting movement and that the principal function of *Fs* is to operate the various contacts 102, 103. From this it is obvious that *Cs* and *Fs* can be combined.

There are two additional features shown in Fig. 3 which also need special mention. The first is the control key lock out. Arranged intermediate the negative battery bar 480 and the control keys is a lock out bar 481 containing circular openings 482 thru which the control keys may be pressed to contact with bar 480 when bar 482 is held in its normal position by biasing spring 483. The opposite end of the bar 481 however, is acted on by magnet 484 in series with the common conductor NB of the relays Re of the analyzer circuits of Fig. 4. Thus, whenever dictation is in progress lock out bar 481 is drawn to the left in which position openings 482 are moved out of registry with the control keys and control movements of the typewriting machine are precluded until dictation has ceased. This prevents premature registration or irregular registration of control movements.

At the upper left of Fig. 3 are shown diagrammatically two small switches X and Y thru which positive battery PB is supplied to the relays of the set 186, 116, 117, 125. Switch X and switch Y are driven by the shaft *us* of the primary register PR. The wipers of the switches are so arranged with respect to their contacts that the one X puts battery on its bus in synchronism with the operation of contacts *o'* to *o⁴* but does not energize its bus 125' between shifts of contacts *o'* to *o⁴*, while the other switch Y has its wiper at 45° to the wiper of switch X and therefore puts battery on its bus 125' only when shaft *us* is operated to shift from one contact *o'* to another *o²* etc., that is, while PR is shifting from one trunk of the group *t'* *t⁴* to another. Thus are premature and irregular operations of the relays of the control group mentioned precluded and

forced to take place in the successive order as respects register devices D as determined by the register itself. Any relays the operation of which it is desired to relate to the 5 primary or secondary registers PR and SR may be similarly controlled.

It is apparent that parallel bars 405 of the machine shown in Figs. 15-17 are none other than the bars B of Fig. 1.

- 10 In Figs. 20 to 23 are shown in enlarged diagrammatic form the switches DS² and PS of Fig. 2 and the switches ES and ES' of Fig. 6. Owing to the limitations of space on the major sheets the switches are there 15 incompletely diagrammed but in Figs. 20-23 these diagrams are complete. The operations of step by step switches as they are actuated from one contact to another of their series and finally come to rest at the end of 20 a given group of the series are so well understood that no special mention of it need be made here. Multiplied groups of contacts are also well understood in their relation to one direction switches. Switch PS is 25 however not a one direction switch but a switch restored to a determinate normal by spiral spring 222. Its normal position is defined by stop 210^a. In this position and in this position only it holds contacts kg 30 closed. Switch ES' in Fig. 21 shows very clearly indeed the relations of contacts 174 and 260 to switch arm 175. The switch arm 175 is of the single ended type but it carries above it a double ended insulating bar 175^a 35 which actuates contacts 174, 260 once each half revolution. It is the projecting end of the upper contact 174 which is struck by the passing end of the bar 175^a and carried upwardly to break with mating contact 174 40 and to make contacts 260. Upper contact 174 then ratchets past the end of bar 175^a just as the latter moves to its resting place. 45 In connection with switch ES is shown a new system of circuits whereby the subscripture magnet is energized in advance of the dating magnet whereby the subscripture shift is brought about before the dating operation takes place. Conductor 236 energized from switch DS² instead of extending 50 directly to magnet 237 as in Fig. 3 extends directly to the subscripture magnet 182 thru the normally closed contacts 165' of the set on the shaft 152 carried just in advance of the abutment 161, and arranged to be actuated 55 by the end of shaft a when the subscripture movement is brought to a finish by the stop 161. Thus this magnet 182 is energized. The movement takes place, the magnet meantime locking up thru contacts 60 182^b and the second pair 165 of the set on the shaft 152. A third pair 165'' is however added to the other two pairs of the set, and when shafts s strike not only are 65 165 and 165' opened unlocking 182, but 165'' is made closing the circuit of the magnet 237

which is to step the switch thru its cycle. This closure effects the first step, and as is fully described hereinbefore its stepping is continued by the operation of the interrupter In. The other circuits associated with the 70 magnet 237 and the magnet 182 are the same as in the preceding forms.

The remaining features of these switches are so readily understood from the diagrams as to not need description. 75

Thus is characterized the system of my invention. As in case of most apparatus of this sort it is of a more or less complicated form in certain parts. It should be understood that in such circuits as usual there are likely to be certain inaccuracies or errors of connection, in general of a character likely to be made by an electrician or a mechanic in setting up such circuits from a diagram, and which the electrician or mechanic thru his skill knows how to correct the moment the error manifests itself thru improper operation or test. The skilled engineer will be even more quickly able to remove such inaccuracies. I have described 80 with great care the interrelation of the parts and the sequence of their operation which are necessary to bring about the desired useful results. Clearly if parts having the adjustments disclosed for any reason upset the 85 interrelation or the sequence of operations described, it is within the province of a person skilled in the art without the exercise of invention to change those adjustments to such a degree as will insure the interrelation and sequence clearly set forth. The 90 means of adjustment known to this art and its kindred arts are very many. Among them may be mentioned fast and slow relays, timing relays, point contacts, wiping contacts, make before break contacts, high and low resistances, etc. Any of these adjustment or their equivalents which are found in the art of telephony and telegraphy I reserve 95 the right of using in case needed to perfect 100 the interrelations and sequence set forth in any case. Timing or sequence of operation is important but once it has been set forth its attainment in the present highly developed state of the arts is merely a matter 105 of mechanical skill. Nor does increase or decrease of the margin of operative sequence involve invention. 110

A number of portions of the system should have special mention in this general connection. First, the analyzer Di, instead of being of the form invented by me may be of any of the forms now known or to be known to the art. Thus either the Ferguson or Flowers types of vocal analyzers may be substituted, provided they are sufficiently efficient for practical use. Ferguson has used a diaphragm analyzer while Flowers has used tuned reeds and tuned circuits. 115 There are still others. I reserve the right 120

- to apply by extension the circuits herein described to any form of typewriter known to the art. Some of them have one form of key board and one form of key shift and some others. The shifting and traversing movements are various. I have already indicated the interchangability of shifting carriages and banks of type bars. Illustrating one in connection with the diagrammatic 10 showing of my invention and the other in connection with the machine feeding rolls of paper. It is apparent that the figures shift key FIGS or its equivalent may be used for paragraph, traverse and the like 15 shifts which may then be dictated to the machine. This means that there would be but one key under the control of the operator and that would be the FIGS key. All other controls would be dictated to the machine while the FIGS key was pressed. The FIGS key always means a word combination, but may not always mean a platen shift. The word dictated determining this thru the combination circuits 101 and it varies with the variation of the keyboard. 20 All numerals on the Universal key board are printed without a platen shift, but on some other machines a platen shift accompanies such printing and is incident to it. 25 However, it is believed that with the advent of commercial systems of this class the typewriting machine will be built especially for the work and not adapted to it. 30 I conceive that there may be use for the register circuits of my invention in connection with the typewriting machines used in the art of printing telegraphy. 35 Finally I desire to have it understood that each of the several branches of the system 40 of my invention as respects operativeness stands on its own foundation. Thus the analyzer itself or the analyzer circuits of Figs. 4 and 5 are capable of performing the functions assigned to them independently 45 of the rest of the system. They may be used with other systems of circuits than those disclosed in Figs. 1, 2 and 3 and 6. As analyzer circuits they stand or fall on their merits as such. So also do the circuits of 50 the primary and secondary registers PR and SR of Fig. 2 and 3, so also individually do the dating and initialling circuits of Fig. 6 and so on. Therefore possible inoperativeness of any of these specially functioning 55 branches of the system has naught to do with the operativeness of any other, and not necessarily with the operativeness of the system at large. Thus the dating and initialling mechanism could be eliminated 60 entirely without affecting the remainder of the system. Thus also the registers could be eliminated and relays Re operated directly upon the actuating magnets w' and w^2 . The interrelations of the branches thru co-

operating interconnections however stand on a somewhat different footing. It is by means of them that the branches are knit together and are appropriately interrelated to form the comprehensive whole.

It goes without saying that all modifications of my invention not falling without its generic spirit are comprehended in the annexed claims.

The stop contacts carried by shaft 152 are of course given any suitable insulated mounting thereon, and flexible connections to their circuits not interfering with the movement of shaft 152.

Instead of control thru switches X and Y of Fig. 3, similar control may be exercised thru relays of the order of relay 80. Also inasmuch as there are in the system disclosed in Figs. 1 to 6 no punctuation mark registers other than the dash register DASH, it is clear that the interlocking circuits for these other punctuation or figure characters may be controlled from contacts actuated from magnets w^2 or relays in the nature of relays 109 and 140 in circuits 101.

Brushes b and b' are of course carried by the platen frame, and in the machine diagrammed in Fig. 1 having a shifting platen connection must be made with them by suitable flexible or trolley, connections as is well understood in the art. Similar means must be employed to take the current into the segment t with which the brushes b b' make contact.

In Fig. 3 there is shown a syllable key SYL the function of which is to effect manually the registration of the dash for syllabizing over circuits 67 connecting with 65.

In addition to operation of figures and caps shift magnets F s and Cs by conductors 245 and 257 when devices ES and ES' are in action, special segments 245^a are provided on each of these devices thru which battery is placed on branch conductor 245^e for the energization of relay 245^b (Fig. 1) the function of which is to open at its contacts the loop 21 controlling the actuation of switch ds and thereby preventing false stepping of this switch. False stepping of this switch occasioned thru any actuation of magnets w' and w^2 except that thru the primary register PR would bring about an abnormal relation of switch ds to trunks t' to t^4 and switch DD, and the relation would only be restored to normal thru the complete loss of several registrations or their record in the wrong order. Switch DS² is also shown in Fig. 22 to be provided with contacts 245^a arranged to be connected with 245^e.

In Fig. 18 is shown a loop y' which is opened when magnet 62 is energized. This loop is intended to be an illustration of a loop in series with the common battery connections of relays Re or Tf which may be

controlled if desired by relay 62 after the fashion and for the purpose of a similar control exercised by relay 62 of Fig. 2 over the common battery connection of relays *rm* 5 of the register PR at contacts 92.

I would mention also that I reserve the right to operate any primary actuating element thru appropriate relay control, to use split contacts where necessary, and to use 10 one direction contacts or its relay equivalent such as relay 40 in group SM, as well known in the art, wherever they may be found necessary to complete a purpose or sequence of operation otherwise clearly described.

15 Obviously all control actions or interoperation coordinates with those described may be carried out by means similar to those described. For instance all characters the imprint of which is surrounded or imposed with 20 the same conditions, are similarly interrelated to other characters and operations, may be secured thru a similar train of operations carried out by a similar train of devices. It has therefore been unnecessary to illustrate 25 all operations or all movements as applying to all characters nor has it been necessary to illustrate the trains of devices applying to all of the movements and operations which will appertain to the commercial machine.

30 What I claim is:

1. A primary vibrational control element comprising a telephone transmitter and a plurality of differently tuned printing control circuits energized under the control of 35 said transmitter and responsive each to a characterizing letter vibration, together with individual printing actuators controlled by the differently tuned printing-control circuits.

40 2. A primary vibrational control element comprising a telephone transmitter and a plurality of differently and adjustably tuned printing control circuits energized under the control of said transmitter and responsive each to a characterizing sound signal vibration, together with individual printing actuators controlled by the differently tuned printing-control circuits.

45 3. A primary vibrational control element comprising a device synthetically responding to sound signals, a plurality of analytical devices commonly acted upon by the energies of said synthetical device to analyze the same, and unitary energy amplifying means intermediate the synthetic and the analytical devices and common to all the analytical devices, together with individual printing actuators controlled by the differently tuned printing-control circuits.

50 60 4. A primary vibrational control element comprising a telephone transmitter and a plurality of differently tuned printing control circuits inductively connected to said transmitter through a common transformer and responsive each to a characteristic sound

signal vibration, together with individual printing actuators controlled by the differently tuned printing-control circuits.

5. A primary vibrational control element comprising a device synthetically responding to sound, a plurality of analytical devices commonly acted upon by the energies of said synthetic device, and a plurality of individual recording elements controlled some from one only of said analytical devices, and some 75 synthetically from a plurality thereof.

6. A primary vibrational control element comprising a device synthetically responding to sound, a plurality of analytical devices commonly acted upon by the energies of said synthetic device to analyze the same, some 80 of said analytical devices being tuned to respond to characterizing tones of signal groups and one at least to respond to the fundamental tones at which the groups are 85 made, and a plurality of individual recording elements of a printing machine controlled from said analytical devices.

7. A primary vibrational control element comprising devices responsive to different signal sound vibrations of the human voice, determinate recording members of a character printing machine normally controlled from determinate analyzer devices, and a switching means arranged to switch certain 90 of said analyzer devices from connection with the normally controlled printing members to other printing members to provide for different spellings of signal groups having substantially the same sound.

8. In combination, a printing machine, a primary vibrational control means controlling the same, figures keys for figures shifts, and an interlock between the figures keys and the control element preventing figures shifts when the primary vibrational control means is in operation.

9. In combination a printing machine which prints in superposed lines, a primary vibrational control means controlling the same, and a signal automatically operable at line beginning to apprise the operator thereof.

10. The method of automatically recording sound signal groups (pronounced word) which consists in utilizing the vibrant energy of the different characterizing sound waves of a given signal sound of a group to produce simultaneously separated dynamic effects, one for each of a plurality of said characterizing waves, and combining said effects to bring about actuation of a single character recording element representing that letter of the word being pronounced at the instant, and effecting group signals through successive energization of a number of independent thus actuated elements.

11. The method of automatically recording sound signal groups which consists in utilizing the vibrant energy of the char-

acterizing sound waves to produce simultaneously separated dynamic effects, controlling the actuation of a single character recording element through the effect of a single wave when the single wave is sufficient to differentially characterize the signal, utilizing a plurality of simultaneously produced separated effects in combination to the same end when a single wave is insufficient to differentiate the signal, and simultaneously annulling the individual controls of the said combined effects.

12. The method of automatically recording sound signal groups which consists in utilizing the vibrant energy of the characterizing sound waves to produce simultaneously separated dynamic effects, controlling the actuation of a single character recording element through a single effect when said effect is sufficient to differentiate the signal to which it pertains from others, utilizing jointly a plurality of said separately produced effects to the same end when one effect is insufficient to differentiate the signal, and

discontinuing all individual control of said effects during the period of continuance of their joint controlling function.

13. The method of automatically recording sound signal groups in lines of limited length which consists in utilizing the vibrant energy of the characterizing sound waves of each signal to produce controlling dynamic effects, controlling the actuation of appropriate character recording elements through said effects, said effects being divided through the sounding of signals in groups and sub-groups into corresponding groups of consecutively produced individual effects separated by time intervals, establishing a determinate test condition when said recording elements operate in proximity to the end of a line, effecting through each of said time intervals a test for said test condition, and effecting the termination of a line through the finding of said conditions.

In testimony whereof he hereunto affixes his signature.

JOHN P. TARBOX.
